Henry Biggins, (Assign. to Nath'l Batchelor) New York City.
Letters Patent (Design No. 60) dated 10th July 1846

The Schedule referred to in these Letters Patent and making part of the same.

To all whom it may concern:

Be it known that I, Nathaniel Batchelor, in connection with Henry Biggins, of the City, County and County and State of New York have invented or produced a new Design to be cast in metal (probably iron) which design when made or cast is intended to be applied or used for a front, or case to a clock; or may be used for the frame of a mirror, or as a guardian or any other or either of them separately or collectively, and I do hereby declare that

the following is a full, clear, and exact description of the same, reference being had to the annexed drawings making a part of this specification, in which Fig. I. is a view of the main or outer frame; Fig. II. is a view of the centre piece or door; and Fig. III. is a view of the whole combined frame, centre piece and guirlande.

Fig. I. of the Frame - This is a piece of scroll, shell and leafage work in the Louis XV style of Architecture. It will be noticed that a. fig. I & III is a raised scroll surrounded with leafage, the base or ground work of which is an irregular circle of shell and leafage work in relief, this also being based upon small pieces of convoluted leafage, b. b. in drawings. United to the before named parts are the scrolls c. c. c. and extended from one side to the other, at the extreme ends of these are branches of leafage, which terminate by their own limitation, these being known as d. d. and may be considered as supported each by a foot. f. f. - These feet connect with other parts by scrolls finishing the base of the frame. From the top of the leaves, d. d. and rising out of said leaves are two columns these being of moulding, or fluted, and the cap of which is a cluster of leafage; these columns may be known as g. g. in the drawings; and the leafage clusters as h. h. next a scroll with braced ends and a centre piece, from which runs inwardly some shell work i. i. - Above these are the scrolls j. j. and yet above them pieces of leafage k. k. mounted by an expanded leaf l. l. We now reach the summit of the design which will be known as m. m. in the drawings, and is a cluster of leafage and scrolls.

Fig. II. The centre piece or door - This is intended as a door, and has an opening through which may be run a clock dial. This opening is surrounded by a wreath of shell and scroll work really mingled together to produce a good effect, see n. in drawings. Below the wreath is a space, which may be filled with a painting or a mirror or other article uniting the taste. See o. in drawings -

By a reference to Fig. III in drawings, it will be seen that

Des. 60

a mirror in the frame as shown in fig. I. This will constitute it a mirror frame.

What we claim as having produced, and wish to secure in Letters Patent, is the above described design, for a frame for a mirror. The same with the addition of the bowed scrolls for a girandole. The same when combined as a whole for a clock frame front; and the whole or either of these parts as set forth and described, or separately.
